UNITED STATES PATENT OFFICE

2,434,014

CONTAINER

Leon J. Rosenberg, Atlanta, Ga., assignor to Gaylord Container Corporation, St. Louis, Mo., a corporation of Maryland

Application June 11, 1945, Serial No. 598,860

9 Claims. (Cl. 229—47)

1

This invention relates to containers, particularly shipping cartons of the kind comprising a body and a slip cover therefor. The principal objects of the present invention are to provide such a carton with a cover fastening means which can be readily mounted in the body of the carton and quickly and easily bent into and out of locking engagement with the cover and which will lie snug against the outer face of the carton when bent into locking position. The invention consists in providing the body of the carton with a fastening member having an exposed upwardly opening hook adapted to receive the lower portion of the rim of the cover and having a portion adapted to extend upwardly through a vertical opening in the cover and to be bent downwardly alongside the rim thereof and thence inwardly beneath said hook. The invention also consists in providing the hook portion of the fastener with a horizontal opening and the fastener with a prong adapted to pass through said opening and penetrate the rim of the cover when the fastener is bent into locking position. The invention also consists in the carton and in the parts and combinations and arrangements of parts hereinafter described and claimed.

In the accompanying drawing, which forms part of this specification and wherein like symbols refer to like parts wherever they occur,

Fig. 1 is a plan view, partly in horizontal section of a shipping carton embodying my invention,

Fig. 2 is a side elevational view of said carton, Fig. 3 is an end elevational view thereof,

Fig. 4 is an enlarged fragmentary and elevational view of the carton in the region of the fastening member,

Fig. 5 is an enlarged vertical cross-sectional view through one end of the carton, the dotted lines showing the fastener in different positions,

Fig. 6 is an enlarged fragmentary horizontal section on the line 6—6 in Fig. 5; and

Fig. 7 is a perspective view of one of the fasteners.

In the accompanying drawing, my invention is shown embodied in a shipping carton of the kind comprising a body A and a slip cover B therefor, both made of corrugated board, fiberboard or other bendable material. The body A may be made from a blank comprising a bottom panel 1 with side wall panels 2 with end flaps 3, and end wall panels 4 with upper marginal flaps 5. The end flaps 3 are bent inwardly and lie against the inner faces of the upturned end wall panels 4; and the upper marginal flaps 5 of said end wall panels are folded inwardly over the top edges of

5 2 said inturned end flaps and thence downwardly against the inner faces thereof to form three-ply end walls. The slip cover B preferably comprises a similarly folded blank comprising a top panel 6 having rim forming side panels 7 with inturned end flaps 8 and reinforcing end panels 9 with upturned lower marginal flaps 10, the end flap 8, end panels 9 and marginal flaps 10 forming three-ply end walls for the rim of the cover. As shown 10 in the drawing, the body A has horizontal slots 11 in its end wall panels 4 and vertical openings 12 in the portions of the end wall panel flaps 5 that extend across the upper edges of the inturned end flaps 3 of the side wall panels 2, said slots and 15 openings being located midway between said side wall panels. The slip cover B fits snugly over the body A with its top panel 6 seated on the upper edges of the side and end walls thereof and with the lower edge of its rim at about the level of the 20 horizontal slots 11 in the outer plies or panels 4 of said end walls; and the top panel 6 of said cover has vertical openings 13 therethrough that register with the vertical openings 12 in the tops of the end walls of said body.

25 The above carton is provided at each end with a fastener C comprising a strap of ductile or pliable metal which has a vertically disposed body portion 14, which is disposed between the end wall panel 4 and the inturned side wall panel flaps 5, and a lower end portion that extends through the horizontal slot 11 in said end wall panel and terminates exteriorly thereof in a preformed upstanding hook 15 adapted to snugly fit the lower portion of the three-ply end wall of the rim of 30 the slip cover B. The body portion 14 of the fastener C extends upwardly through the vertical opening 13 in the top panel 6 of the cover A and terminates in a preformed outwardly curved upper end portion 16. The cover 13 is locked to the body 35 A by bending the exposed upper portion of the body portion 14 of the fastener downwardly and outwardly against the top panel 6 of the cover B, thence downwardly alongside of the rim panel 9 and the hook 15 at the lower end of said fastener and thence inwardly to bring the curved free end 16 of said body portion beneath said hook.

40 As shown in the drawing, the upwardly extending hook-forming lower end of the fastener C has an opening 17 extending horizontally therethrough; and the portion of the fastener which overlaps said opening has a sharp pointed projection or prong 18 struck therefrom at an upwardly inclined angle thereto, which prong is 45 adapted to extend through said opening and to

be forced or thrust into the rim of the cover when the fastener is bent into locking position. In order to prevent the prong 18 of the fastener from interfering with passage of the body portion 14 thereof through the openings 11, 12 and 13, the fastener is initially made with the prong disposed entirely in the plane of said body portion. After the cover B is applied to the body A, the free end 16 of the body portion 14 of the fastener is bent laterally along the base of the prong so as to 10 bend the latter at an oblique angle to said body portion.

The hereinbefore described construction has several important advantages. The cover fastener C is simple and inexpensive and can be quickly and easily mounted in the body of the carton with its upper end disposed vertically in position to pass through the opening 13 in the top panel 6 of the cover B when the latter is applied to said body. The hooked lower end 15 of the fastener provides a seat and retainer for the lower portion of the rim of the cover B and the fastener may be quickly and easily bent around the rim and beneath said hook. During the bending of the fastener into locking position, the prong 18 is extended through the horizontal opening 17 in the hook 15 and penetrates the rim of the cover, thus preventing the bent free end portion 16 of the fastener from springing outwardly and snagging persons or objects. The fastener serves to securely lock the cover to the body of the carton, thereby permitting the carton to be lifted by means of the cover. The fastener may be readily released to permit the cover to be detached for inspection or removal of the contents of the carton merely by pulling the free end of the fastener outwardly to disengage the prong 18 from the rim of the cover and from the opening 17 in the hook 15 and then bending the fastener upwardly into vertical alignment with the vertical opening 13 in the cover. The prong 18 may be bent flat so as to prevent it from snagging in the opening 13 of the cover B when the latter is removed from the body A.

While my invention is shown embodied in a carton of the folded-blank type, it is obviously applicable to containers of other types.

What I claim is:

1. A container comprising a body and a cover therefor having a rim portion disposed along the outer side of said body and a vertical opening adjacent to said rim portion, and a fastener mounted in said body and having an upwardly directed hook located exteriorly thereof adapted to receive the lower portion of said rim portion and a portion adapted to extend upwardly through said opening and to be bent downwardly alongside said rim portion and said exposed hook, said hook having an opening therethrough and said portion of said fastener having a prong thereon adapted in the downwardly bent position thereof to extend through said opening and to penetrate said rim portion from the outside thereof.

2. A container comprising a body and a cover therefor having a rim portion disposed along the outer side of said body and a vertical opening adjacent to said rim portion, and a fastener mounted in said body and having an upwardly directed hook located exteriorly thereof adapted to receive the lower portion of said rim portion and a portion adapted to extend upwardly through said opening and to be bent downwardly alongside said rim portion and said exposed hook, said hook having a horizontal opening therethrough and said portion of said fastener

having a prong thereon adapted in the downwardly bent position thereof to extend through said opening and to penetrate said rim portion from the outside thereof, said prong being bendable into and out of the plane of said portion of said fastener.

3. A container comprising a body and a cover therefor having a rim portion disposed along the outer side of said body and a vertical opening adjacent to said rim portion, and a fastener mounted in said body and having an upwardly directed hook located exteriorly thereof adapted to receive the lower portion of said rim portion and a portion adapted to extend upwardly through said opening and to be bent downwardly alongside said rim portion and said exposed hook, said hook having an opening therethrough and said portion of said fastener being also adapted to be bent beneath said hook and having a prong thereon adapted in the downwardly bent position thereof to extend through said opening and to penetrate said rim portion from the outside thereof in an upwardly inclined direction.

4. A container comprising a body and a cover therefor having a rim portion disposed along the outer side of said body and a vertical opening adjacent to said rim portion, said body having a horizontal opening in said outer side thereof, and a fastener mounted in said body and having a lower portion extending outwardly through said horizontal opening and thence upwardly to form an exposed upwardly directed hook adapted to receive the lower portion of said rim portion, and a portion adapted to extend upwardly through said opening in said cover and to be bent downwardly alongside of said upwardly extending hook forming portion and thence beneath said outwardly extending hook forming portion.

5. The combination set forth in claim 4 wherein said upwardly extending hook forming portion has a horizontal opening therethrough and said fastener has a prong thereon adapted to extend through said last mentioned opening into said rim portion.

6. A carton comprising a body having a multi-ply wall with a horizontal opening through the outer ply thereof, a cover having a rim portion disposed along the outer side of said wall and a vertical opening above the top thereof, and a fastener having a portion mounted in said wall between adjacent plies thereof, a portion extending outwardly through the horizontal opening in the outer ply and thence upwardly to form a hook adapted to receive the lower portion of said rim portion, and a portion extending upwardly through the vertical opening in said cover, said last mentioned portion being adapted to be bent downwardly alongside of said rim portion and the upwardly bent hook forming portion and thence beneath the outwardly extending hook forming portion.

7. The combination set forth in claim 6 wherein in said upwardly bent hook forming portion has a horizontal opening therethrough and said downwardly bent portion has a prong projecting therefrom adapted to extend through said last mentioned opening and penetrate said rim portion.

8. A carton comprising a body having side wall panels with inwardly bent end flaps, end wall panels disposed along the outer sides of said inwardly bent flaps and having upper marginal flaps that are bent over the upper edges of said inwardly bent flaps and thence downwardly along

the inner side faces thereof, said end wall panels and their upper marginal flaps and said inwardly bent end flaps forming multi-ply end walls, a slip cover for said body having a rim portion fitting around said side and end wall panels and vertical openings above the latter, said end wall panels having horizontal openings therethrough below said rim portion and said upper marginal flaps having vertical openings therethrough above said inwardly bent end flaps, and a fastener mounted 10 in each of the end walls of said body, said fastener comprising a body portion interposed between the end wall panel and the inturned side wall flaps, a portion extending outwardly through the horizontal openings in said end wall panel and thence upwardly to form a hook adapted to receive the lower portion of the rim portion of 15 said cover and a portion adapted to extend upwardly through the vertical opening in said upper marginal flap and said cover to be bent downwardly along the outer face of said rim portion and the upwardly extending hook forming por-

tion and thence inwardly beneath the outwardly extending hook forming portion.

9. The combination set forth in claim 8 wherein the upwardly bent hook forming portion has a horizontal opening therethrough and the downwardly bent portion has a prong thereon adapted to extend through said upwardly bent portion and to penetrate said rim portion.
